DONALD NOBLE, OF BRIDGEPORT, CONNECTICUT, ASSIGNOR TO THE SINGER MANUFACTURING COMPANY, A CORPORATION OF NEW JERSEY.

STOP-MOTION MECHANISM FOR SEWING-MACHINES.

1,121,655.

Specification of Letters Patent. Patented Dec. 22, 1914.

Application filed March 19, 1913. Serial No. 755,285.

To all whom it may concern:

Be it known that I, DONALD NOBLE, a subject of the King of Great Britain, residing at Bridgeport, in the county of Fairfield 5 and State of Connecticut, have invented certain new and useful Improvements in Stop-Motion Mechanism for Sewing-Machines, of which the following is a specification, reference being had therein to the accompanying drawings.

This invention relates to improvements in stop-motion mechanism for sewing machines and is especially designed for use in connection with blind stitch sewing machines 15 which form stitches alternately in and outside of the fabric, as when employing an ordinary zigzag sewing machine for overedging, and has for its object to arrest the action of the machine only when forming an outside stitch, as distinguished from the commonly employed stop-motion mechanisms for arresting the action of the machine when the needle is out of the fabric, regardless of the character of the stitch 25 being formed.

The present construction of stop-motion mechanism is shown and described as applied to the blind stitch sewing machine represented by U. S. patent application Serial No. 660,255, filed November 14, 1911, 30 D. Noble, and while this particular machine differs somewhat from the earlier devices, it is believed that sufficient of the details in construction is herein shown to clearly illustrate the application of the present improvement.

Figure 1 is a view in side elevation of a blind stitch sewing machine and its power-transmitting mechanism equipped with the present invention; Fig. 2 a rear end view of the machine, the machine frame being shown in section to better illustrate certain details in construction later to be referred to, together with a view of the power-transmitting mechanism shown in the previous figure; Fig. 3 a view looking in the direction indicated by the arrow *t*, Fig. 2, showing the machine frame in section, and also showing in section and in full lines certain elements important to an understanding of the prime members of the connections for effecting the automatic control of the stop-motion mechanism; and Fig. 4 a plan view of certain elements shown in the previous figures which are important to an understanding of the manual and automatic control of the stop-motion mechanism.

1 represents the sewing machine frame in which is mounted in suitable bearings the main shaft 2 carrying at one end a belt-pulley or hand-wheel 3 and at its opposite end a flange 4.

5 is an oscillating cylinder having formed integral with it a bearing stud 6 mounted in a suitable bearing 7 formed in said frame, said stud being held against endwise movement by suitable nuts (not shown) fitted upon the end of the shaft opposite that carrying said cylinder.

8 represents a needle-carrying bar mounted in the cylinder 5 and having endwise movements in a substantially horizontal plane, said bar being provided at its forward end with a needle-bracket 9 in which is suitably secured an eye-pointed needle 10, and coacting with said needle is an oscillating thread-carrying loop-taker 11 provided with the usual bobbin 12 and with a suitable hook shaft (not shown) having oscillatory movements in the same plane as the stitch-forming movements of the needle-bar, the latter and said hook-shaft being operatively connected, through suitable connections, with a pitman 13 connected by a crank 14 carried by the flange 4 secured upon the main shaft 2.

From the foregoing it is to be understood that through the shaft flange 4 and its pitman 13, horizontal movements are transmitted to the needle-bar 8 and oscillatory movements to the loop-taker 11 to form stitches.

As is well understood, in the formation of a blind stitch seam the needle passes alternately through and outside of the fabric, and when piercing the fabric enters and emerges from the same side thereof, and this in the present instance is accomplished by giving to the cylinder 5 a rocking movement with respect to the plane of the fabric being stitched.

Upon the main shaft 2 is secured a gear 15 which meshes with a gear 16 carried by the feed-actuating shaft 17, and as said gears are of the ratio of two to one, the shaft 17 is given one rotation to two rotations of the shaft 2. Secured to the forward end of the shaft 17 is a feed-disk 18 provided with an adjustably secured connection 19 which cooperates with a suitable friction pawl and disk (not shown) secured upon the feed-shaft 20, and upon the end 21 of the shaft 17 is secured a flange 21' in which is

secured a pin 22 with its axis eccentric to that of said shaft, and swiveled on said pin is a block 23 which works in a groove 24 formed in an extended portion 25 of the oscillating cylinder 5, whereby oscillatory movements are transmitted to said cylinder to cause the stitch-forming mechanism to place stitches alternately in and outside of the fabric. Upon the end of the shaft 20 10 opposite that carrying the feed-disk (not shown) is secured a bevel gear 26 which meshes with a gear 27 carried by an oscillating feed-shaft 28, upon the free end of which are secured serrated rotary feed-disks 15 29 and 30, thus transmitting step-by-step feed movements to the disks 29 and 30, through the feeding elements described.

A rock-lever 31 is pivoted upon a shaft 32 mounted in the frame 1 and provided at its forward end with a pin 33 which enters a suitable opening in the lower end of the fabric ridge-forming blade 34. Mounted in suitable bearings formed in the frame 1 is a horizontally arranged shaft 35 having secured upon one end a rock-lever 36, one end of which coacts with an eccentric 37, carried by the flange 21', which enters a suitable slot (not shown) formed in said lever, the rotation of said eccentric causing said lever 30 30 to be rocked upon its fulcrum. The opposite end of the rock-lever 36 is divided and provided with oppositely arranged bearings, as 38, in which is trunnioned a short shaft 39 through which passes a standard 40 secured at its lower end on a rock-shaft 41 carried by the rock-lever 31, said standard being threaded at its upper end to receive an adjusting nut 42 provided with a slightly tapered threaded portion 43 upon which is threaded a securing nut 44, the nut 42 being provided with a depending portion 45. Thus it will be seen that through the adjustment of the nut 42, vertical adjustment of the ridge-forming blade is effected when, 45 for any purpose, it is desired to change the operative relationship of the upper end of said blade with respect to the line of needle actuation, a spring 46 seated at its lower end on the hub 47 of the standard 40 and having its upper end in contact with the inner end wall of the housing 48 threaded into the frame 1 normally acting to hold said ridge-forming blade in its elevated position.

50 The shafts 20 and 28 are mounted in suitable bearings formed in the transversely arranged sections 49 and 50 of the shaft bracket 51, and upon the section 50 is secured by pinch screw 51', one end of a lever 60 52, the opposite end of which is pivotally attached to an upright rod 53 which passes through a housing 54 threaded into the frame 1 and is provided at its upper end with an adjusting nut 55 having an extended tapered portion 56 provided with a secur-

ing nut 57, and mounted upon the rod 53 is a spiral spring 58 the upper end of which contacts with the inner wall of the housing 54 while its lower end is seated upon a collar 59 secured upon said rod, thus through the action of said spring the feed-disks 29 and 30 are resiliently held in their elevated or effective positions with respect to the fabric being acted upon.

The cloth-presser comprises an upright 75 threaded portion 60 provided at its lower end with a suitable cross bar (not shown), to which is pivoted by suitable screws, as 61, the swinging presser-foot 62. The portion 60 passes through a vertical tubular portion 80 63 formed integral with a horizontal arm 64 slidably mounted in a suitable tubular opening (not shown) in a bracket 65 secured upon the cylinder 5, a suitable spring (not shown) located in the tubular portion 63 and surrounding the upright portion 60 acting to hold the presser-foot 62 down upon the fabric. The horizontal arm 64 is free to oscillate in the tubular bearing formed in the bracket 65, its movement in the direction of 90 its length being in opposition to the resiliency of a suitable spring (not shown) mounted on a reduced portion (not shown) located within the opening in said bracket 65, said spring being held confined within 95 said opening by a nut 66.

The machine is operated from the source of power through a suitable power transmitter depending from the underside of the sewing machine table, which comprises a 100 power transmitter bracket 67 in which is secured a pulley-shaft 68 provided with a tight pulley 69 and loose pulley 70, the pulley 69 being provided with a washer or friction element 71. A suitable belt (not 105 shown) acts to connect the pulley 70 with the source of power, and a like connection (not shown) acts to connect the pulley 69 with the belt-pulley or hand-wheel 3.

72 represents a brake-actuating lever and 110 73 a brake lever, the latter carrying a brake element or shoe 74 which, at the will of the operator, coacts with the tight pulley 69 to arrest the action of the machine, the levers 72 and 73 being fast on a shaft 75 having 115 rocking movements in suitable bearings located in the bracket 67, a spring 76 normally acting to hold said brake shoe in contact with the pulley 69.

77 represents a power-transmitting lever, 120 one end of which is secured upon the shaft 75, its opposite end 78 being provided with an inclined surface 79 which, when the brake shoe 74 is manually moved away from the pulley 69, acts on the end of the short 125 shaft 80 to move the loose pulley 70 into engagement with the friction washer 71, thus effecting a driving and driven relationship between said pulleys.

To manually effect the downward adjust- 120

ment of the feed-disks 29 and 30 and blade 34, as when placing the fabric into or out of operative relationship with the stitch-forming mechanism, there is provided a rod 81, 5 the lower end of which is secured to a foot treadle 81', its upper end being pivotally attached to a collar 82 which, in turn, is secured upon a tubular rod 83 provided at its upper end with a cross bar 84 which, when 10 moved vertically through a rocking movement of the treadle 81' in the direction indicated by the arrow *u*, or in a direction opposite that for starting the machine, contacts with a forked arm 85 of a bracket 86 secured 15 by screws 87 upon a rock-shaft 88 mounted in suitable bearings in the frame 1, said rock-shaft being provided with a bracket 89 carrying lugs 90 and 91, and as said rock-shaft is actuated by the vertical movements 20 of the rods 81 and 83, the lugs 90 and 91 are brought into contact with the underside of the levers 52 and 31, respectively, and in the further movement of said rods said levers are rocked upon their fulcrums to position 25 the feed-rolls 29 and 30 and ridge-forming blade 34 in their lowest or fabric-receiving positions.

The starting of the machine is effected by a movement of the foot treadle in a direction opposite that indicated by the arrow *u*, which causes the lower end of the tubular rod 83 to depress the outer end of the brake-actuating lever, thus releasing the brake 74 and moving the incline 79 to force the loose 35 pulley 70 into driving engagement with the tight pulley 69.

To arrest the action of the machine only at alternate stitches, or when forming the stitch placed outside of the fabric, there is 40 provided a rod 92 which is pivoted at its lower end to the free end of the brake-actuating lever 72 and passes through the tubular rod 83, the rod 92 at its upper end being provided with an enlarged portion 93 and shoulder or step 94, from which latter extends upward a guiding member 95. During the operation of the machine the shoulder 94 is held slightly below the under surface of the releasing lever 96 mounted upon 45 a fulcrum pin 97 threaded into the base 1, until the operator releases her control of the foot treadle, when said shoulder is moved into contact with the underside of the lever 96, where it remains until released by the 50 action of the cam 98 (in opposition to the resiliency of the spring 98') on the roller 99 carried by the lever 96, which allows the spring 76 to rock the shaft 75 and force the brake shoe 74 into contact with the tight 55 pulley 69, and the incline 79 out of effective engagement with the short shaft 80. The cam 98 is positioned so that it acts on the roller 99 only when an outside stitch is 60

being formed, the effective action of the brake shoe thus being coincident with the 65 formation of an edge or outside stitch.

I claim—

1. In a sewing machine provided with a thread-carrying needle having stitch-forming movements in a path intersecting the 70 fabric being acted upon and in a path outside of said fabric, the combination with power-transmitting mechanism for transmitting power from the supply to the machine, and a stop-motion mechanism for arresting the action of said machine, of means under the control of the operator for interrupting said transmission of power and bringing said stop-motion mechanism into 75 action, and automatically controlled means for preventing the effective action of said stop-motion mechanism except when the needle is actuated to form an outside stitch. 80

2. In a sewing machine provided with a thread-carrying needle having stitch-forming movements in a substantially horizontal plane intersecting the fabric being acted upon and in a substantially horizontal plane outside of said fabric, the combination with power-transmitting mechanism for transmitting power from the supply to the machine, and a stop-motion mechanism for arresting the action of said machine, of means under the control of the operator for interrupting said transmission of power and bringing said stop-motion mechanism into 95 action, and automatically controlled means for preventing the effective action of said stop-motion mechanism except when the needle is actuated to form an outside stitch. 100

3. In a sewing machine provided with a thread-carrying needle having stitch-forming movements in a substantially horizontal plane intersecting the fabric being acted upon and in a substantially horizontal plane outside of said fabric, the combination with power-transmitting mechanism for transmitting power from the supply to the machine, and a stop-motion mechanism for arresting the action of said machine, of means under the control of the operator for interrupting said transmission of power and bringing said stop-motion mechanism into 105 action, and automatically controlled means for preventing the effective action of said stop-motion mechanism except when the needle is actuated to form stitches only in a given plane. 110

In testimony whereof, I have signed my name to this specification, in the presence of 120 two subscribing witnesses.

DONALD NOBLE.
